UNITED STATES PATENT OFFICE.

HENRY M. GREEN, OF LOS ANGELES, CALIFORNIA.

LOCKED-PACKING PUMP PLUNGER.

Application filed April 10, 1924. Serial No. 705,537.

To all whom it may concern:

Be it known that I, HENRY M. GREEN, a citizen of the United States, residing at Los Angeles, in the county of Los Angeles and State of California, have invented new and useful Improvements in Locked-Packings Pump Plungers, of which the following is a specification.

This invention relates to deep well and other plunger pumps and more particularly to plungers.

An object is to provide a pump plunger having a substantially continuous tubular body upon which there is mounted a plural- 15 ity of expandible packers made for instance of hemp, and an object is to provide means for assembling the packers in locked position on the tubular body.

Another object of this invention is to assemble a series of cups on a tubular body, there being an expandible packing disposed in the cups and locked therein against removal by means of liners, which also serve to space the cups from each other, the whole 25 series of cups being held in locked position.

Another object is to provide unit packers, consisting of a cup with a liner locking the packing in position, so that the packing 30 cup may be easily assembled or disassembled on the tubular body.

Other objects and advantages will be made manifest in the following specification of an embodiment of the invention illustrated in the accompanying drawings, wherein—

Figure 1 is a side elevation of the improved plunger.

Fig. 2 is a longitudinal central section of 40 the plunger.

Fig. 3 is an enlarged fragmentary sectional detail view of the plunger.

Figs. 4, 5 and 6 are vertical cross sections of a packing cup, and assembly means 45 showing the successive steps of placing and locking the packing in position within the cup.

Fig. 7 is a vertical cross section of the cup, with packing and liner in position.

The plunger of this invention includes a 50 tubular body 2 of suitable dimensions and proportions, the lower end of the tube being provided with threads 2^a, and the up-

per end with threads 2^b. On the lower threads 2^a is screwed a thimble 3 one end of 55 which is bored out to form a chamber 3^a annularly around the contiguous part of the body 2.

On the upper end of the plunger body 2 is screwed a working valve 4. Below this 60 valve there is run on the threads a follower 5 consisting of an internally threaded collar.

Loosely slideable along the smooth outer surface of the body 2 is a series of collar-like packing cups 6, the cavities of which 65 are all set in one direction and adapted to receive an expandible cylindrical body of packing 7, which may be of any suitable soft material, such as hemp. The lower end of the packing 7 is disposed within the cup 6, 70 the upper end of the packing 7 is free to expand from the absorption of the liquid in the barrel, within which the tubular body is disposed to form therewith a fluid tight seal, 75 as will be understood.

The packing 7 is firmly locked in position within the cups 6 by means of a sleeve-like liner 8 surrounding the tubular body 2. The liner 8 has its lower end inwardly tapered, as at 8^a, and rests upon the bottom 80 of the cup 6, which, to provide further retaining means for the packing, is provided on its interior wall with circular grooves 6^a.

As will be seen from Fig. 3, the packing 7 forms an expanded lower end in the cup 6 and also engages the grooves 6^a and will be thus securely locked against removal from the cup 6. Each cup 6, with the exception of the lowermost cup, rests upon a sleeve liner 8 and the whole series of packing 85 cups with the packing, forms one continuous packing unit when the follower 5 is screwed down upon the tubular body locking the entire series of cups against the thimble 3.

I prefer to assemble the packing and the liner in each individual cup, as shown in Figs. 4 to 7 inclusive, in which 9 represents a cuplike form, preferably made of metal, having a reduced central cuplike 95 chamber 9^a. The packing cup 6 is disposed within the form 9 and a cylindrical rod 10 is centrally placed in the cuplike chamber 9^a. The soft packing 7 is next placed within the cup 6 and a sleeve 11, tapered at its 100 lower end 11^a and snugly fitting the rod 10, 105

is pushed down over the rod 10, down to the bottom of the chamber 9^a. The object of this manipulation to compress in part the packing 7 and move it toward the walls of the cup 6.

The next step is to place the sleeve-like liner 8 over the sleeve 11, which it fits snugly, and force it down through the packing 7, the tapered ends 8^a of the liner 8 will 10 serve to force the packing toward the walls of the cup and the circular grooves 6^a. At the end of this operation the packing will be disposed within the cup 6, as shown in Fig. 6.

15 The next step is then to remove the cup 6 with its packing 7 and liner 8 from the form 9, which may be done by lowering the form 9 with the rod 10 and sleeve 11, leaving the cup 6 with its packing 7 and liner 20 8, as shown in Fig. 7.

In practice it is only the packings of the cups at the opposite ends of the assembled series which will expand by the absorption of the liquid with which it comes in contact. As the packing cups of the opposite ends become worn, the packing of adjacent cups will successively expand and form a liquid tight seal. Where it is desired to 25 replace the packing, it is only necessary 30 to remove the thimble 3, slip off the packing cups 6 and replace them with cups with fresh packing.

From the above it will be seen that I have provided a pump plunger having a series 25 of longitudinally spaced and independently mounted expandable packers, the packing of each packing cup being subjected to a substantially equal degree of compression, and which will therefore operate to expand with 40 approximately equal frictional pressure against the pump cylinder or barrel in which the plunger may be working, as it is successively called into service, as explained above.

45 Various changes in the construction and arrangement may be made by those skilled in the art without departing from the spirit of my invention, as claimed.

I claim:

1. In a plunger, the combination of a 50 tubular body, packing cups mounted thereon, said packing cups having expandible packer retaining grooves within the inner walls, sleeve liners surrounding the tubular body and having tapered lower ends 55 engaging the bottom of the cups and locking the packers in the cups, said liners serving to space the cups from each other on the tubular body, and means for locking the cups in assembled position on the tubular 60 body.

2. In a plunger, the combination of a tubular body, packing cups mounted thereon, each cup being provided with an expandible packer, and a sleeve liner surrounding the tubular body and engaging the bottom of the cups and locking the packing within the cup, said liners serving to space the cups from each other on the tubular body, and means for locking the cups and 70 liners in assembled position on the tubular body.

3. In a plunger, the combination of a tubular body, a series of packer retaining units mounted along the body, means for locking the packer within the units and spacing them from each other, and means for locking the units in assembled position 75 on the tubular body.

4. In a plunger, the combination of a 80 tubular body, a thimble attached to the lower end of the body, a follower threaded on the upper end of the body, and a series of independently mounted expandible packers arranged in spaced relation along the 85 body, cups having chambers receiving the end of one packer and liners between the cups surrounding the body, said liners locking the packers within the cups and spacing the cups from each other, whereby the series 90 of cups and the packers may be locked in spaced relation upon the body.

In testimony whereof I have signed my name to this specification.

H. M. GREEN.
